UNITED STATES PATENT OFFICE

2,382,252

MEANS FOR CONTROLLING DUST IN THE SCREENING OF DUST-LADEN MATERIAL

Walter J. Parks, Cleveland Heights, Ohio, assignor to The W. S. Tyler Company, Cleveland, Ohio, a corporation of Ohio

Application December 9, 1941, Serial No. 422,256

6 Claims. (Cl. 209—370)

This invention relates, as indicated, to means for controlling dust in the screening of dust-laden materials.

Various attempts have heretofore been made to combat the problem of controlling the spreading of dust in the screening of dust-laden materials, so as to eliminate, as far as possible, the hazards to the health of laborers and others working about screening apparatus employed in screening such materials.

It has been common practice in the screening art to completely enclose vibrating screen bodies by attaching cover plates rigidly to the same, but except on small and light units, this has not proven satisfactory because (1) the weight of the covers and the necessary stiffeners thereon constituted an additional load on the bearings and materially reduced the life expectancy of the same, (2) the attachment of the covers in such a manner as to make the joints dust tight required a multiplicity of bolts or other cover-secur ing devices which increased, to an objectionable point, the time required to change screen cloths within the enclosed body, and (3) flexible connections of canvas or rubber were required at the feed inlet, oversize discharge and fines outlet points and it was difficult to make such connections permanently dust-tight due to the vibration loosening the connections and the rapid deterioration of the material.

The present invention has as its primary object the provision of a method of and means for controlling dust in the screening of dust-laden materials, which are free from all of the aforesaid disadvantages, and which are highly effective in reducing to a minimum the aforesaid hazards to the health of laborers and others working about screening apparatus employed in screening such materials.

Another object of the invention is to provide means of the character described, which is mounted directly on the non-vibrating or non-gyrating parts of the screening machine, so as to be free from the vibrating or gyratory movement of the screen body. This permits the use of cover plates of minimum thickness, the use of a relatively small number of cover plate securing devices, and the use of rigid air removal connections, which can be made dust-tight.

Another object of the invention is to provide an air seal enclosure consisting of a relatively light open frame, permitting ready access to the screen cloth tensioning bolts.

A further object of the invention is to provide an air seal enclosure forming air passageways

or openings with the screen body, which openings can be varied in size.

Other objects and advantages of the invention will be apparent during the course of the following description.

In the accompanying drawings, forming a part of this specification, and in which like numerals are employed to designate like parts throughout the same,

Fig. 1 is a front end elevation of a screening machine having incorporated therein the novel enclosure air seal of the present invention;

Fig. 2 is a side elevation of the aforesaid screening machine;

Fig. 3 is a longitudinal broken cross-sectional view of the machine taken on the line 3—3 of Fig. 1;

Fig. 4 is a fragmentary longitudinal cross-sectional view, through the upper portion of the feed end of the apparatus, taken on the line 4—4 of Fig. 1;

Fig. 5 is a fragmentary horizontal cross-sectional view, through the apparatus, taken on the line 5—5 of Fig. 2;

Fig. 6 is a fragmentary transverse cross-sectional view through the apparatus, taken on the line 6—6 of Fig. 2;

Fig. 7 is a view similar to Fig. 4, but showing a modified form of structure;

Fig. 8 is a view similar to Fig. 5, but showing a modified form of structure;

Fig. 9 is a view similar to Fig. 6, but showing a modified form of structure;

Fig. 10 is a fragmentary elevational view, showing a modification in the means for securing the cover plates to the air seal enclosure, and

Fig. 11 is a cross-sectional view, taken on the line 11—11 of Fig. 10.

The novel enclosure or air seal of the present invention may be incorporated in various types of screens, but for purposes of illustration, is here shown as embodied in a gyratory screen, such for example, as the type disclosed in my United States Patent No. 2,066,362.

Such a screen consists essentially of a stationary supporting base or frame, a screen body, and means for imparting a gyratory movement to the screen body. The base, or frame in this case, consists of a pair of transversely spaced base rails 1, in the form of I-beams, connected by a plurality of longitudinally spaced I-beams 2, the base rails having secured to the ends thereof plates 3, to which are secured cables C; whereby the base frame may be flexibly suspended, pref-

erably in an inclined position, from any desired superstructure (not shown).

The screen body, in this case, which is disposed within the base frame, comprises a pair of transversely spaced side plates 4 and 5, which are disposed in planes parallel with but spaced inwardly of the base rails, and screens 6 and 7 which extend transversely of said side plates, the upper screen 6 being of coarser mesh than the lower screen 7. The screen body is resiliently mounted on the base rails, as by means of resilient supports generally indicated at 8, and is provided with a transversely extending shaft 9, which extends through the side plates and upon rotation of which a gyratory movement is imparted to the screen body. The shaft 9 is supported at its ends in gyratory supporting bodies 10, which, in turn, are resiliently mounted on the base rails, as by means of resilient supports generally indicated at 11.

The novel enclosure or air seal will now be described in detail.

The enclosure, in its preferred form, consists of a rectangular frame mounted adjacent to each side plate, on the base frame of the machine so that there are formed restricted openings, or clearances, between each member of the frame and the adjacent edge of the vibrating side plates of the machine. Specifically this rectangular frame consists of four upright angles, 12 and 13 of Fig. 2 being adjacent to the ends of side plate 4 on one side of the screen body and 14 and 15 of Fig. 5 being adjacent to the ends of the other side plate 5 on the opposite side of the body; two longitudinally extending angles, 16 and 17, mounted on top of said uprights and running along, and adjacent to, the top of the side plates 4 and 5, respectively; and two bottom members running from the bottom of the uprights parallel and adjacent to the bottom of the side plates 4 and 5. These bottom members are represented by the angle 52 in Fig. 9, or in a modified form by the bent angle 46 and rubber strip 45 of Fig. 6.

Mounted on the members 16 and 17 are suitable cover plates 20, which are removable, as by means of handles 21, to permit access to the screen body, and a feed plate 22, the latter being mounted on a rearward extension of the members 16 and 17, and having an opening 23 therein for the feeding of the materials to be screened. The cover plates 20 may be secured to the members 16 and 17 in the manner shown in Fig. 6, that is, by means of bolts 24 pivoted to pins 26 mounted in brackets 27 which are bolted to the members 16 and 17. The bolts 24 extend through slotted openings in the edges of the cover plates 20, and nuts 28 are secured to the bolts above these openings. This provides a ready means of securing the cover plates to the enclosure or air seal, and permits easy removal of such plates, when necessary.

Secured, in a removable manner, to the angles 13 and 14 is a discharge plate 29 (Fig. 3), having openings 30 and 31 therein for the discharge of the sized materials from the upper and lower screens respectively.

At the rear of the enclosure or air seal is a chamber P (Figs. 4 and 5), which may be termed a plenum chamber, since air sucked through the spaces between the screen body and the enclosure is drawn into this space before being removed from the screen. This plenum chamber is formed by means of triangular shaped side plates 32 and 33 which are secured to the uprights 12 and 15, and a back plate 34, which is secured, as by means of the angles 35 to said side plates. The space

between the upper end of the back plate 35 and the feed plate 22 is filled by an angle cross-member 36, which is bolted to said feed plate (Fig. 4). A conduit 37 for removal of air from the plenum chamber is secured to the back 35, as best shown in Fig. 3.

The enclosure which is thus provided may be rigidly connected to the base frame by means of bolts and rivets, but is preferably mounted in the following manner. The discharge end section is constructed as a rigid upright unit consisting of the upright angles 13 and 14 and the discharge plate 29 (Fig. 3) which is fastened to the discharge end cross beam 2, by means of the hinged connection 38 (Fig. 1) and held in place by means of the angles 18 and 19 (Fig. 2) attached to the body and the base frame respectively in such a manner that when the bolts joining the two are removed the upright unit can be swung outwardly away from the screen body. The feed end section is also constructed as a unit consisting of the upright angles 12 and 15, the triangular shaped plates 32 and 33 and the back plate 34 similarly hinged to the cross beam 2 at the feed end of the screen and secured to angles 18 and 19 at that end. The top section is also constructed as a rigid unit consisting of the longitudinal angles 16 and 17, the feed plate 22, the cross member 36 and other cross members as required but not including the detachable cover plates which bolt to flanged members on top of the upright angles. This construction permits the rapid dis-assembly of the enclosure if for any reason, as for example if the screen body is to be removed from the base frame as a unit, complete access to the screen body is necessary. In this case the flanged joint connecting either end of the top section to its upright support can be unbolted and the complete unit of the top section and the other end section can be swung back out of the way, or the connections at both ends can be unfastened and each end section swung independently away from the screen body. This eliminates the necessity of unbolting each separate part of each unit and results in a very important saving of time when such an operation is necessary.

The material passing through the bottom deck of the vibrating screen body drops through the opening enclosed by the members 2 and 46 of Fig. 3. This opening, if not restricted, would necessitate the handling of an excessive amount of air to maintain a constant inwardly directed current. To avoid this a fines hopper 84, either furnished with the machine or provided by the user, is attached to the members 2 and 46 and is so constructed that it tapers from the large area enclosed by the said members to a small opening 85, just sufficiently large to accommodate the discharge of the material passing that point.

Similarly, to stop an excess inflow of air through the openings 30 and 31 and, at the same time, to permit the free discharge of material through the same, flexible curtains 49, of rubber or other material, are preferably hung within them as shown in Fig. 3.

It will be noted that in Figs. 5 and 6 the openings between the outside enclosure and the vibrating screen body is formed by the members of the enclosure and metallic angles mounted on the side plates of the machine except in the case of the opening along the bottom of the side plate shown in Fig. 6, where the edge of the side plate itself forms one side of the opening and the rubber skirt plate 45 forms the other side. The side plate itself could have been used to form

one side of the opening all the way around but due to the fact that at various places on the side-plates there are protuberances of various kinds, including bolt heads, that would require the enclosure to be spaced farther from the screen body in order to maintain the proper and safe operating clearances for the vibrating body, it is preferable to extend the sideplates outwardly beyond any such interference by means of the angles shown or by bending the plate itself outwardly. This latter construction is not shown.

Furthermore, to control the amount of air entering through the openings around the side-plates, the construction shown in Figs. 8 and 9 may be used. In these figures bars of rigid material or of flexible material such as rubber are bolted to the angles 50, 51, 53 and 54 so that they may allow the full opening between the vibrating body and the enclosure as shown or they may be turned over so that the outward edge projects beyond the end of the angles and further restricts the openings 39', 40', 41' and 44' through which the air passes to enter the body. This restricted opening is shown by the dotted lines.

Fig. 8 also illustrates a modified form of construction as applied to the plenum chamber. In some cases, as will be brought out later, this plenum chamber is not used and in that case the backplate of this chamber will not be in the position shown in Fig. 4 but the extension members 33 shown in Fig. 4 will be eliminated and the backplate brought into the position shown by 34" of Fig. 8 and bolted directly to the uprights 15'.

In general, the structure above described consists of a stationary box-like enclosure completely surrounding the vibrating screen body, except for an area, on either side of the screen body, approximately equal to, and completely exposing, the area of the side plate. The enclosure is provided with the necessary openings 23, 30, 31 and 85 of Fig. 3 to deliver to and discharge from the screen surfaces the material to be treated and these openings together with the restricted passageways 30, 40, 41 and 44 of Figs. 5 and 6 are the only points of communication between the interior of the screen body and the atmosphere.

In addition to the openings above described leading to the atmosphere, there are various openings in the interior of the machine between various parts where it is desirable to control the passage of the air. For example, in Fig. 4 it will be seen that as the material passes from the feed opening 23 onto the feed plate of the screen it is subjected to the direct suction from the plenum chamber and if the opening was unrestricted this suction might draw larger particles than desired from the material into the air stream. In order to eliminate this possibility an additional seal, 48, is fastened to the cover plate angle 36. In a modified form this same seal is shown as 48' of Fig. 7. In Fig. 4 the seal is attached to the cover plate angle and is not disturbed when the backplate 34 is removed from the backplate 34' and comes off with it when removed from the machine. As the motion of the screen body is such that the body moves directly towards and away from this seal, it is preferably made of an elastic or resilient material curved outwardly from end to end so that if the body travels or shifts enough to touch it in its cyclic motion the member will give or deform easily and not cause any damage to the machine itself.

Such air that is drawn into the screen body,

as through the discharge openings 30 and 31, openings 49, 41 and 44, is drawn into the plenum chamber P through the back plate 47 of the screen body, which back plate is perforated for this purpose as shown at 47' in Figs. 4 and 5.

The plenum chamber, which has been described, is provided for the purpose of regulating the velocity and distribution of air removal, and its location may be varied from that shown, the location and construction thereof being determined by considerations such as the point at which it is most feasible to remove the air. Moreover, it is not essential that a plenum chamber be used, and if such a chamber is not used, air removal may be accomplished through the discharge plate, through the fines hopper which is usually provided at the bottom of the screen, or through the side plate of the screen body. In the latter case, an unperforated back plate would be used on the screen body instead of the perforated plate 47.

The air removal system which has been described is designed primarily to dampen the dust in the material which is being screened, and to avoid discharge of such dust into the atmosphere about the screen. Accordingly, air from the space surrounding the screen is drawn into the screen body through the openings 40, 41 and 44, passing downwardly through the material being screened from the top of the screen body and passing upwardly through such material from the bottom of the screen body to the center of the screen, as indicated by the arrows in Fig. 6. This air is drawn into the plenum chamber through properly proportioned holes in the screen body back plate 47, and, together with such air as enters the plenum chamber directly through the openings 39, 42 and 43, is drawn from the plenum chamber by means of an air collecting system, adapted to be connected to the conduit 37. The velocity of the air within the screen body may be controlled by varying the size of the openings at the points 40, 41 and 44, and in such a manner as to lay the dust, i. e., keep the dust within the screen body rather than to carry it out of the screen body.

It will be noted that during the gyratory movement of the screen body, the openings 39, 40 and 41 are not varied in size, since the portions of the enclosure adjacent these openings are parallel with the side plates of the screen body. This permits the velocity of the air to remain substantially uniform throughout the screening operations, an important consideration, since pronounced variations in the air velocity may cause an undesirable swirling of the dust.

It will be further noted that since the sides of the air seal frame or enclosure are open, access to the screen cloth tensioning bolts, seen in Fig. 2, may be had for adjustment and other purposes.

It is thus seen that I have provided a method of and means for controlling dust in the screening of dust-laden materials, which overcome all of the disadvantages to which reference has hereinbefore been made. Since the air seal or enclosure is mounted directly on the stationary base frame of the screen, it is not subjected to the vibratory or gyratory action of the screen body, so that the cover plates may be made as thin as desirable without causing flexing thereof, and without imposing any burden on the bearings. Moreover, it is not necessary, in order to make the cover plates dust-tight, to employ an excessive number of bolts or other cover-securing devices,

so that the work of removing and replacing the cover plates is reduced to a minimum. Furthermore, it is not necessary to provide flexible connections, which are difficult to make dust-tight, at the feed and discharge points of the screen body for the removal of the dust, and a rigid conduit for the air exhaust, such as 37, may be directly connected to the air seal frame by a dust-tight connection. Since the air-seal frame is stationary, the chutes (not shown), which are usually provided for carrying the sized material from the screens through the openings 30 and 31, may be rigidly connected to the discharge plate, or a flexible connection may be used between the screens and the discharge plate.

Referring to Figs. 10 and 11, the cover plates 20, in this case, are removably secured to the air seal enclosure, one member 16 of which is shown, by means of spring hooks 60, which are pivotally secured to the frame of the air seal enclosure and are provided with hook ends 61, which are adapted to overlie the cover plates, and handles or finger pieces 62, whereby the hooks are swung, relatively to the cover plates.

It is to be understood that the form of my invention, herewith shown and described, is to be taken as a preferred example of the same, and that various changes in the shape, size and arrangement of parts, may be resorted to, without departing from the spirit of my invention, or the scope of the subjoined claims.

Having thus described my invention, I claim:

1. In a screening mechanism, a base, a screen member mounted on said base for reciprocatory movement, an enclosure for said screen member, comprising a casing structure surrounding the screen and mounted on said base independently of the screen mounting and spaced from the screen, said casing structure comprising a skeleton frame made up of end uprights projecting from the base and longitudinal members connecting the upper and lower ends of the uprights together, end walls for the casing structure having discharge openings therein, and a cover, and bottom wall completing the casing structure, the space between the uprights and longitudinal connecting members at the sides of the casing structure constituting elongated openings, and an outlet on the casing through which suction may be applied.

2. In a screening mechanism, a base, a plurality of superposed screens connected together by side plates mounted on said base for reciprocatory movement, an enclosure for said screens comprising a casing structure surrounding the screens and mounted on said base independently of the mounting for the screens and in spaced relation to said screens, said casing comprising end walls, side walls, and bottom and top walls, the side walls each having an elongated opening therein of an area slightly less than the area of the screen connecting plates and lying adjacent thereto, and means for drawing air through said openings, and against the side plates to direct the air both above and below the screens.

3. In a screening mechanism, a base, a plurality of superposed screens connected together by

side plates mounted on said base for reciprocatory movement, an enclosure for said screens comprising a casing structure surrounding the screens and mounted on said base independently of the mounting for the screens and in spaced relation to said screens, said casing comprising end walls, side walls, and bottom and top walls, the side walls each having an elongated opening therein of an area slightly less than the area of the screen connecting plates and lying adjacent thereto, and means for drawing air through said openings, and against the side plates to direct the air both above and below the screens, said side plates being provided with means for varying the space between said plates and casing to vary the flow of the air as it passes above and below the screens.

4. In a screening mechanism, a base, a plurality of superposed screens connected together by side plates mounted on said base for reciprocatory movement, an enclosure for said screens comprising a casing structure surrounding the screens and mounted on said base independently of the mounting for the screens and in spaced relation to said screens, said casing comprising end walls, side walls and bottom and top walls, the side walls each having an elongated opening therein of an area slightly less than the area of the screen connecting plates and lying adjacent thereto, and means for drawing air through said openings, and against the side plates to direct the air both above and below the screens, said side plates being provided with strips which may be projected toward or away from the sides of the casing to vary the flow of air as it passes above and below the screens.

5. In a screening mechanism, a base, a screen mounted for reciprocatory movement on said base, an enclosure for said screen comprising a casing structure surrounding the screen and mounted on the base independently of the screen mounting and spaced from the screen, said casing structure comprising side, end and bottom walls and removable cover plates, said side walls having elongated openings therein through which air is drawn into the casing, a back wall on said screen spaced from one end wall and being provided with properly proportioned perforations through which air is drawn from the casing.

6. In a screening mechanism, a base, a screen member mounted on said base for reciprocatory movement, an enclosure for said screen member comprising a casing structure surrounding the screen and mounted on said base independently of the screen mounting and spaced from the screen, said casing including side, bottom and top walls and two end walls, one having a discharge opening therein for screened material and the opposite end wall having an opening therein through which air is drawn from the interior of the casing, said end walls being hinged to a portion of the casing so as to swing downwardly and outwardly from the side walls of the casing to permit access to the screen and the side walls of the casing being provided with openings through which air is drawn into the casing.

WALTER J. PARKS.
